SPRING WINDING TOOL

John Blaer, Sharon, Pa.

Application April 10, 1935, Serial No. 15,655

1 Claim. (Cl. 153—67)

This invention relates to a tool especially adapted for the construction of coil springs and has for the primary object the provision of a portable device which may be easily applied and supported by a vise and like device and is so constructed that it may be manually operated and adjusted to form springs of any desired pitch either of the coiled compression or extension types and is capable of coiling either square or round wire of any length and gauge.

With these and other objects in view this invention consists in certain novel features of construction, combination and arrangement of parts to be hereinafter more fully described and claimed.

For a complete understanding of my invention, reference is to be had to the following description and accompanying drawing, in which

Figure 1 is a perspective view illustrating a tool constructed in accordance with my invention.

Figure 2 is a vertical sectional view illustrating the same.

Figure 3 is a side elevation illustrating the tool supported by a vise.

Figure 4 is a detail sectional view illustrating the mounting of the mandrel to the holder or body of the tool.

Figure 5 is a detail longitudinal sectional view showing the adjustable spring pitch device and also illustrating the wire feeder or guide to the mandrel.

Referring in detail to the drawing, the numeral 1 indicates a body or holder of the tool which has one end reduced, as shown at 2, to be received between and gripped by jaws of a vise 3 as disclosed by Figure 3. The holder or body 1 is of substantially rectangular shape in cross section and when in use is supported vertically by the vise. A chamber 4 is formed in the body and opens outwardly through the lower end of the latter. Opposite walls of the body are provided with mandrel receiving openings 5 which communicate with the chamber 4 and in which is rotatably mounted a mandrel 6. The mandrel is engaged by a jaw 7 slidably mounted in the chamber 4 and is adjusted towards the mandrel by a set bolt 8 threaded to the body. The active face of the jaw 7 is substantially V-shaped, as shown in Figure 4, and the lower walls of the openings 5 are correspondingly shaped so that the mandrel may be effectively supported for rotation with endwise movement and with a desired drag thereon. A pin or handle 9 is secured to the jaw and extends through a slot 10 in the

body for lifting the jaw 7 away from the mandrel after the jaw has been released by the set bolt 8.

A lever 11 is apertured to receive the mandrel and is removably secured to said mandrel by a set bolt 12. The lever 11 has a handle 13 whereby the mandrel may be conveniently rotated. The lever 11 adjacent the apertures thereof is provided with an enlargement to receive a set bolt 14 and said enlargement is provided with an opening 15 to receive one end of a wire to be coiled about the mandrel. The set bolt 14 may be adjusted for securing the wire in the opening 15.

The body 1 adjacent the mandrel is provided with an opening to receive a bolt 16 carrying spaced washers 17 to form a guide in the feeding of the wire onto the mandrel. By adjusting the bolt 16 in the opening of the body the grip of the washers 17 on the wire may be varied.

An adjusting bolt 18 is threaded to the body and has an annular collar 19 fitting in a notch 20 of a slidably mounted adjusting bar 21. The adjusting bar parallels the mandrel and is slidably supported by the body 1 and has removably secured to one end a wire engaging plate 22. The plate 22 has an inclined face or edge 23 engageable with the mandrel and also a convolution of the wire upon the mandrel. By adjusting the position of the plate 22 relative to the wire feeder the relations of the convolutions relative to one another being formed in the wire on the mandrel can be varied so that the convolutions may be formed of different pitches. The plate 22 with its adjusting means forms a pitch varying device and permits the forming of coil springs of different pitches upon the mandrel.

In operation, wire of a selected gauge and shape is passed through the wire feeder and secured to the lever 11 and by rotating the mandrel 40 through the lever 11 the wire will be caused to coil about the mandrel and by adjusting the pitch means the coil spring formed on the mandrel from said wire may be made of a desired or selected pitch.

Having described the invention, I claim:

A spring winding tool comprising a body having a chamber and provided with openings in opposite walls communicating with the chamber, a mandrel mounted in said openings for rotatable and slidable movements, a jaw slidably mounted in the chamber to engage the mandrel, means for adjusting the jaw against the mandrel to permit rotation and endwise sliding movements thereof, a lever for rotating the mandrel 50 55

and adjustably and detachably connected to the latter, a wire guide carried by the body for directing a wire onto the mandrel, means for connecting one end of the wire to the lever, a bar 5 slidably mounted on the body and having a notch, a pitch varying plate carried by one end of said bar and engageable with the wire on the

mandrel, and an adjusting bolt threaded to the body and having an annular flange extending into the notch whereby the pitch varying plate may be adjusted endwise of the mandrel in either direction.

JOHN BLANER.
